ELECTRIC SELECTION CONTROLLING
CIRCUIT

Henry F. Herbig, Madison, N. J., assignor to International Standard Electric Corporation, New York, N. Y., a corporation of Delaware

Application May 6, 1943, Serial No. 485,827

17 Claims. (Cl. 179—18)

This invention relates to new and useful improvements in selection control circuits and more particularly to circuits for controlling the numerical selecting operation of selector switches employed in automatic telephone exchange systems.

The present is an improvement on the control circuits disclosed in the co-pending application of Gerald Deakin, Serial No. 484,184, filed April 23, 1943, and in the various applications and patents referred to therein.

The invention will be explained with reference to Figs. 1 to 5 of the drawings which diagrammatically illustrate four modifications of as much of a control circuit, embodying the various features of the present invention, as is necessary for a clear understanding thereof.

In an automatic telephone system calling and called subscribers' stations 1 and 2 (Fig. 1) may be inter-connected by means including a plurality of selector switches 3 and 4. The numerical operations of the selectors are controlled by the calling subscriber's customary impulse sender or other number indicating device through the agency of a register provided at the central exchange. The calling station 1 is connected to the brushes of selector 3 by non-numerical switches and a connecting circuit 6, and the register is attached to the connecting circuit 6 through switching means 5.

The selector switches are of the customary type having a bank of terminals with which a set of brushes cooperates. In the drawings three brushes are shown for selector 3 although the selector may have a larger number of brushes. The selector brushes are moved over the terminals while a magnet P is energized and are stopped on a set of terminals when this magnet becomes de-energized.

The register comprises a series of switches successively operable by the calling device in accordance with the successive digits of the called number. A brush and a set of terminals of one of these register switches is shown in Fig. 1. This is the register switch which responds to the digit destined for selector 3. When brush RB is advanced towards one of ten terminals (only four of which are shown) in accordance with the operation of the calling device at the station 1, the register starting relay RSR, having been energized in the customary manner, a circuit is closed from ground over the armature and back contact of a relay GVR in the register, the armature and front contact of relay RSR in the register, the contacts of preceding selectors, the winding of a

selector relay AR, to grounded battery. AR operates and closes a parallel energizing circuit for the selector magnet P. In its back contact AR removes the normal ground from the selector to brush T.

The magnet P starts the brushes of the selector 3 to move over the terminals and will continue until GVR becomes energized.

The energization of relay GVR is controlled by 10 a gas valve GV having a cathode C, an anode A and a control electrode CE. The control electrode CE is connected over a $200,000\omega$ resistance R5 and a $300,000\omega$ resistance R3 with a high tension battery HTB. The anode A of the gas valve 15 is connected over a 1000ω resistance R6 and the winding of relay GVR with battery. The cathode C being grounded, the relay GVR will be energized when the gas valve ionizes. This in turn is controlled by two vacuum tubes V1 and V2. 20 The vacuum tubes V1 and V2 are tetrodes in which the screen grid is connected with the cathode. Triodes having suitable characteristics could be used but the employment of tetrodes in the manner described enables smaller voltage 25 steps to be employed. Tetrodes of the type RCA.50L6GT have been used and enable the system to operate satisfactorily when their filaments are run at about half their rated voltage. The two tubes may be provided within the same bulb 30 or in separate bulbs. The gas valve GV may be of any commercial type, the one disclosed being of the customary three-electrode cold cathode type.

Various potentials may be applied to the electrodes of V1 and V2 over register brush RB and 35 selector brush T. The potentials applied to the grid of the first tube V1 and the cathode of the second tube over register brush RB and the potentials applied over selector brush T to the cathode of the first tube V1 and the control grid of the second tube V2 are indicated in Fig. 2. The 40 potentials in the selector are applied over 600ω resistances R1 and those in the register over 100ω resistances R3. The control grids are connected over resistances R1 and R2. Thirteen different negative D. C. potentials, two volts apart, 45 are assigned for designating the ten digits of a line number and three operating conditions, i. e. the busy condition of a line, the calling condition of a line and erroneous or slow operation of the 50 calling dial.

Whenever the potentials applied to the electrodes of the two tubes V1 and V2 over the selector and register brushes is not the same, then current will flow in the plate circuit of one tube or the other over the common branch of these

plate circuits which leads to the high tension battery HTB. The control electrode CE of the gas valve GV connected with this common branch is kept below the potential necessary for the ionization of the gas valve. However, when both control grids have the same potential as their respective cathodes, then the current flowing in this common branch of the plate circuits will not be appreciable and the potential of the control electrode CE will rise to the full potential of the high tension battery, thus causing the gas valve GV to ionize and operate the relay GVR.

When the relay GVR operates, it opens in its back contact the energizing circuit of the selector power magnet P stopping the selector on the test terminals of the line to which the same negative potential is connected as to the terminal on which the register brush RB is resting.

The establishment of the complete connection is continued in the same manner.

The brush RB remains in contact with a terminal when it first touches the next terminal thus momentarily bridging two terminals, which will prevent the opening of the connections to the cathode of V2 and control grid of V1. The selector brush T cannot be arranged to bridge two terminals, since the selector terminals are multiplied. To guard against false operation of tubes V1 and V2 when brush T leaves a terminal, the circuit leading to this brush is grounded over a 1 megohm resistance R4.

In Fig. 3, an arrangement is disclosed in which only two triodes are used in the register, the gas valve being eliminated. Instead of distinguishing between the terminals engaged by the register and the selector brushes by only voltage differences, the distinction is made both by voltage and polarity differences. Thus, the first five terminals of both the register and the selector may be connected to 6, 12, 18, 24 and 30 volt taps of negative battery and the second group of five terminals to similar taps of positive battery. The adjacent terminals may be graded by other than 6 volt steps.

When the selector brush T is hunting over test terminals the potential of which is more negative than the potential applied to the terminal on which brush RB is resting, then the control grid of tube V1 which is connected with brush T over a resistance R3 will be more negative than the cathode of this tube which is connected with brush RB over a resistance R2. The grid of tube V2 which is connected with brush RB and with the grid of V1 by a resistance R1 will, therefore, be positive with respect to the cathode of this tube which is connected with brush T of the selector. While this condition prevails, the plate current of tube V1 will be substantially zero and the plate current of tube V2 will be at its saturation value causing the closing of an energizing circuit for relay VR2 over the high tension battery to ground over the front contact and armature of a relay X in the register which is energized at that time.

If the conditions were reversed as to the relative polarities of the terminals with which the two brushes are in engagement, then the relay VR1 would become energized and the relay VR2 remain de-energized.

While one or both these two relays remain de-energized the circuit of the power magnet P of the selector (which, as in the previous case was established over armatures and front contacts of relays AR and RSR) will also remain closed

over the back contact and armature of one of the two relays VR1 or VR2 to ground.

Upon the reversal of the potentials applied to the control grids when the selector and register brushes engage the first terminal connected to positive battery, the relay VR2 releases while the relay VR1 operates. If during this short transmit time the selector magnet P should release before VR2 applies its holding ground through its back contact, then a condenser C may be used between the break springs of relays VR1 and VR2 and ground. The charging current flowing through this condenser would keep the magnet P of the selectors energized until the ground is restored at one of the relay contacts.

When the brush T of the selector contacts with a terminal that has the same potential and polarity of the terminal on which the register brush is resting, then the grids of the two tubes

20 V1 and V2 will be at the same potential as their respective cathodes, i. e. at substantially zero potential. No current can flow over R1. The plate circuit of each tube will reach the saturation point and both relays VR1 and VR2 will be 25 operated at the same time. This will remove ground from the circuit of the power magnet P and the selector will be stopped with its b brushes on the terminal selected.

Upon the operation of relays VR1 and VR2, 30 a short-circuit is closed over the inner front contacts and armatures of these relays around the resistance R1 to keep the grids of the two tubes at their respective cathode potentials when the brush T of the selector is momentarily grounded for a busy condition.

The resistance R1 may have a value of 1 megohm or more which will eliminate any induction interference that might be produced during the hunting of the selector brush T over its 40 terminals. Resistances R2 and R3 which are connected in series with those brushes may be 1000-2000 ω so as to limit the current to less than .020 ampere during the short time a busy ground over the back contact of relay AR is applied to brush T. HTB is a high tension battery of approximately 100 volts.

Here as in Fig. 1 the test conductor is grounded over resistance R4, which may be provided in the register or the selector.

50 In the arrangement shown in Fig. 4, the two vacuum tubes V1 and V2 are used in conjunction with a four-rectifier bridge and a single winding quick releasing relay VR or, as shown in Fig. 5 a double wound relay VR and two rectifiers S1 and S2.

The two triodes V1 and V2 have the characteristic that the plate current is more or less proportional to the grid potential and polarity. Only when the grids of the two tubes are at the 60 same potential and have the same polarity will the plate currents and plate potentials of the two tubes be equal.

When the plate potentials are equal then current flows from the high tension battery HTB over an armature and front contact of the register relay RSR (this contact is for the sake of clarity shown as mechanically separated from the relay) and thence through the resistances R1 and R2 to the plates of the two vacuum tubes. 70 No current will flow through the winding of relay VR in the rectifier bridge. However, when the potential of one of the grids, e. g. of V1, is greater than that of the other, then current will flow not only through R1 but also through R2, rectifier S3, the winding of relay VR and

rectifier S4. Thus, relay VR will operate whenever the plate potentials are unequal. The rectifier bridge is so arranged that the current flow will always be in the same direction so that a shift of the controlling potential from V1 to V2 or vice versa will not cause VR to release.

When RB is advanced to a terminal and the relay RSR is energized, unequal current will flow since the grid of tube V2 will find a ground applied over the armature and back contact of the selector relay AR. When the AR becomes energized then ground is applied to this grid over resistance R4. It will be noted that the ground applied through the armature and back contact of relay AR cannot reach the register brushes RB except through the very high resistances R3 and R4.

When the test brush T reaches the terminal that has the same polarity as the terminal on which RB is resting, then no current will flow through relay VR. This relay releases and opens the energizing circuits of relay AR and power magnet P thus stopping the selector.

The current flow over the test wire during selection is so small that it does not tend to develop cross-talk. The arrangement of the battery connections to the selector and register terminals is the same as in Fig. 3.

This arrangement permits the use of directly heated cathodes whereby the filament circuit may be open when the register is idle without fear of delay when the register is subsequently picked up and the filament circuit is again closed. Directly heating filaments go into an emitting condition almost instantly after the closing of the filament circuit.

What is claimed is:

1. In combination, a selector switch having a plurality of first contacts and a second contact a magnet for controlling the contacting of the second with any first contact, a register having a plurality of first contacts and a second contact, means for contacting the second register contact with any first contact of the register, a control circuit extending from said register to the magnet of said selector, relay means in said register for controlling said circuit, two vacuum tubes in said register each having a cathode, a grid and an anode electrode, a connection from the second register contact to one electrode of the first tube, a connection from the second selector contact to the corresponding electrode of the second tube, a source of potential, connections for applying different potentials to each first contact of the register and selector, and a circuit for operating said relay means jointly controlled by said vacuum tubes.

2. The combination of claim 1 and in which said source is a source of D. C. potentials, and said connections from the second contacts of the register and selector are to the grids of the two tubes.

3. The combination of claim 1 and in which the potentials applied to the first contacts of the register are the same as those applied to those of the selector, and the vacuum tubes cause the operation of the relay means if contact is made in the selector with a first contact to which the same potential is applied as to the first contact with which the second contact of the register is in engagement.

4. The combination of claim 1, and in which said source is a source of D. C. potentials, the second contact of the register is connected to the grid of the first tube and the cathode of the sec-

ond tube, and the second contact of the selector is connected to the cathode of the first tube and the grid of the second tube.

5. The combination of claim 1, and in which a gas valve is provided between said tubes and said relay means.

6. The combination of claim 1, and in which said relay means comprises two relays, one connected with the anode of each tube, the circuit of the selector magnet being controlled over back contacts of said relays in parallel.

7. The combination of claim 1, and in which the relay means consists of a relay having a contact controlling the circuit of the selector magnet, and in which direct current potentials are connected over the second contacts of the register and selector to the grids of the tubes, an energizing circuit for said relay including the anodes of said tubes, and rectifiers in said energizing circuit.

8. In combination, a selector switch having a plurality of terminals and a set of cooperating brushes, a magnet for controlling the operation of said brushes, a register comprising a switch having a plurality of terminals and a brush adapted successively to engage them, means for operating the register brush to engage any terminal, a control circuit extending from said register to the magnet of said selector, relay means in said register for controlling said circuit, two vacuum tubes in said register each having a cathode, a grid and an anode, a connection from the register brush to the grid of the first tube, a connection from the selector brush to the grid of the second tube, a source of D. C. potential, connections for applying the same potentials to the terminals of the register and selector switches, there being a predetermined voltage difference between the potentials applied to adjacent terminals, and a circuit for operating said relay means jointly controlled by said vacuum tubes.

9. The combination according to claim 8 and in which said connection from the register brush includes also the cathode of the second tube and said connection from the selector brush to the cathode of the first tube.

10. In combination, a selector switch having a plurality of terminals and a set of cooperating brushes, a magnet for operating said brushes, a register comprising a switch having a plurality of terminals and a brush adapted successively to engage them, means for operating the register brush to engage any terminal, a control circuit extending from said register to the magnet of said selector, a relay in said register for controlling said circuit, a valve having a control electrode, a cathode and an anode, an energizing circuit for said relay including said anode, two vacuum tubes in said register each having a cathode, a grid and an anode, a connection from the register brush to the grid of the first tube and the cathode of the second tube, a connection from the selector brush to the grid of the second tube and the cathode of the first tube, a source of D. C. potential, connections for applying the same potentials to the terminals of the register and selector switches, there being a predetermined voltage difference between the potentials applied to adjacent terminals, and a connection from the anodes of the two tubes in multiple to the control electrode of the valve.

11. In combination, a selector switch having a plurality of terminals and a set of cooperating brushes, a magnet for operating said brushes, a register comprising a switch having a plurality

of terminals and a brush adapted successively to engage them, means for operating the register brush to engage any terminal, a control circuit extending from said register to the magnet of said selector, a relay in said register for controlling said circuit, a grounded high tension battery, a gas valve having a control electrode connected with said battery, a grounded cathode and an anode connected over the winding of said relay with said battery, two vacuum tubes in said register each having a cathode, a control and a screen grid and an anode, a connection from the register brush to the control grid of the first tube and the cathode and screen grid of the second tube, a connection from the selector brush to the control grid of the second tube and the cathode and screen grid of the first tube, a source of D. C. potential, connections for applying from said source potentials of the same voltage and polarity to the terminals of the register and selector switches, there being a predetermined voltage difference between the potentials applied to adjacent terminals, and a connection from the anodes of the two tubes in multiple to the control electrode of the gas valve.

12. In combination, a selector switch having a plurality of terminals and a set of cooperating brushes, a magnet for operating said brushes, a register comprising a switch having a plurality of terminals and a brush adapted successively to engage them, means for operating the register brush to engage any terminal, a control circuit extending from said register to the magnet of said selector, two relays in said register each having a contact for controlling said circuits, two vacuum tubes in said register each having a cathode, a grid and an anode, a connection from the register brush to the grid of the first tube and the cathode of the second tube, a connection from the selector brush to the grid of the second tube and the cathode of the first tube, a source of D. C. potential, connections for applying the same potentials to the terminals of the register and selector switches, negative potentials to some and positive potentials to other terminals, there being a predetermined voltage difference between the potentials applied to adjacent terminals, a circuit for operating one relay including the anode of the first and a circuit for operating the other relay including the anode of the second tube.

13. In combination, a selector switch having a plurality of terminals and a set of cooperating brushes, a magnet for operating said brushes, a register comprising a switch having a plurality of terminals and a brush adapted successively to engage them, means for operating the register brush to engage any terminal, a relay for said register having a contact controlling the selector magnet, two vacuum tubes in said register each having a cathode, a grid and an anode, a connection from the register brush to the grid of

the first tube, a connection from the selector brush to the grid of the second tube, a source of D. C. potential, connections for applying the same potentials to the terminals of the register 5 and the selector switches, positive to some and negative to others, there being a predetermined difference between the potentials applied to adjacent terminals, an energizing circuit for said relay connected to the anodes of both tubes, and rectifiers in said bridge allowing the flow of current over said relay only in one direction.

14. An electrical control system comprising a selector device having a contact brush, actuating means for moving said brush successively over 15 a plurality of positions, means for applying a characteristic potential to said brush in each of said positions, control means for controlling said actuating means, an electron discharge means including first and second electron discharge paths each comprising a cathode, an anode and a control grid electrode, a connection from said brush to said control grid electrode of said first path and cathode of said second path, means for applying a predetermined potential to the control grid electrode of said second path and the cathode of said first path and a connection from 20 said two anodes in parallel to said control means.

15. An electrical control system according to claim 14 wherein each said discharge path also 25 comprises a further grid electrode located between the respective control grid electrode and anode and directly connected to the respective cathode.

16. A switching arrangement for a telecommunication system comprising a register switch having a plurality of contacts and a cooperating contact brush, means for applying a characteristic potential to each of said contacts, means for operating said register brush to engage any said contact, a selector switch having a plurality of contacts and a cooperating contact brush, means for applying a characteristic potential to each of said selector contacts, actuating means for controlling the movement of said selector brush over its contacts, a control device for said actuating means, an electron discharge means including first and second discharge paths each comprising a cathode, an anode and a control grid electrode, a connection from said register brush to the control grid electrode of said first path and the cathode of said second path, a connection from said selector brush to the cathode of said first path and the control grid electrode of said second path, and a connection from said 40 50 55 two anodes in parallel to said control device.

17. An electrical control system according to claim 16 wherein each said discharge path also 60 comprises a further grid electrode located between the respective control grid electrode and anode and directly connected to the respective cathode.

HENRY F. HERBIG.
